ABSTRACT

A simple hydraulically operated label die cutting machine wherein the ram which forces a stack of labels through the cutting die, and a shuttle which moves a stack of labels into position over the ram, are both hydraulically operated. The shuttle and ram operate in timed relation to each other automatically. Provision is made for jogging either the ram or the shuttle independently of each other. A safety switch is provided to stop the machine if the operator's hand is still on a stack of labels being moved into position by the shuttle when the stack of labels is about to enter into position over the ram. Additional safety for the operator is provided by relatively low pressure operation of the piston which actuates the shuttle, so that the shuttle can be held manually without great exertion. The cutting die is held by two pairs of mutually opposed chuck jaws whereby the die may be adjusted linearly in two directions at right angles to each other, and the chuck jaws are mounted on a plate which may be rotated and clamped in the desired position for the rotational alignment with the stack. The die holding portion of the machine is anchored to the main machine frame which carries the ram cylinder by means of corner posts, which thus take the strain of the die cutting operation.

HYDRAULIC LABEL DIE CUTTING MACHINE

BRIEF SUMMARY OF THE INVENTION

In the past, label die cutting machines have been mechanical in operation. This involved the use of a fly wheel and various eccentrics and mechanical linkages which made these machines heavy and expensive. According to the present invention the ram and shuttle are hydraulically operated, thus making the machine much lighter and considerably less expensive. Hydraulic operation also makes possible a built-in safety feature which will be described in more detail hereinafter.

A pump is driven by an electric motor and feeds a hydraulic circuit including the ram cylinder and the shuttle cylinder. The movement of the ram piston is controlled by a four-way valve which in one position feeds fluid below the piston to move the ram up and in another position feeds fluid above the piston to move the ram down. Fluid also passes through this valve to feed a shuttle circuit.

The shuttle circuit feeds the shuttle cylinder through a four-way valve which in one position causes the piston to move the shuttle in and in another position to move the shuttle out. The shuttle circuit is provided with a pressure relief by-pass valve to sump and this pressure relief valve is set at a relatively low pressure, say 65 psi, while the ram circuit operates at, say 1,100 psi. All the valves are solenoid operated and the solenoids are actuated by several limit switches at appropriate times.

The die holding portion of the machine is secured to the main frame of the machine by heavy corner posts which take the entire die cutting load of the machine. The corner posts are actually screws which are interconnected and by means of which the vertical position of the die holder may be adjusted. The cutting die is held by means of two pairs of chuck jaws disposed in guides at right angles to each other. By advancing one jaw of a pair while retracting the other, the die may be adjusted along one axis. By similar operation of the other pair of jaws, the die may be adjusted along an axis at right angles to the first axis. The several chuck jaws are mounted on a plate which may be rotated and then clamped in a desired position so that the die may be rotationally adjusted as well.

An electric circuit is provided, including switches and valve operated solenoids, and is arranged so that either the ram or the shuttle may be jogged individually for setting up adjustment, or the machine may be caused to operate automatically with the shuttle and ram operating in relation to each other.

BRIEF DESCRIPTION OF THE DRAWINGS

FIG. 1 is a isometric view of the base of the machine with the die holding portion removed.

FIG. 2 is an isometric view of the die holding portion of the machine.

FIG. 3 is a detailed exploded isometric view of one of the chuck jaws showing its construction.

FIG. 4 is a fragmentary rear elevational view with parts shown in vertical cross section.

FIG. 5 is a detailed view of the safety switch mechanism as seen from the front of the machine.

FIG. 6 is a diagram of the hydraulic circuit; and

FIG. 7 is a diagram of the electrical circuit.

DETAILED DESCRIPTION

Basically, as seen in FIG. 1, the machine frame is enclosed within a cabinet 10. At the top of this cabinet is the feeding table 11 and the die holding portion of the machine is supported on the screws 12 shown fragmentarily in FIG. 1. The ram 13 rises through an aperture 14 in the table to force a stack of labels placed thereon upwardly through the cutting die. The labels are moved into position on the ram by means of a shuttle 15 passing through a slot 16 in the table 11.

The top plate 17 is adjustable vertically by means of the somewhat diagrammatically shown mechanism including a nut on each of the screws 12 associated with 15 a sprocket 12a and with all of the sprockets 12a embraced by a sprocket chain 12b. The sprocket associated with the screw 12 at the left of FIG. 2 is provided with a wrench element 18 and when this wrench is turned, the sprocket associated therewith transmits rotation to all the other sprockets through the chain 12b and thereby the plate 17 is raised or lowered.

The top plate 17 has a circular aperture 19 and rotatably mounted immediately beneath it is the lower plate 20 which has the square aperture 21. The plate 20 carries a plurality of studs 22 on which rollers 23 are mounted and the rollers 23 engage the inner periphery of the circular aperture 12 in the top plate 17. A plurality of clamp members 24 serve to clamp the bottom plate 20 in position with respect to the top plate 17. Rotary adjustment of the plate 20 is accomplished as best seen in FIG. 4 by means of a screw 25 axially fixed in a depending lug 26 forming a part of the top plate. The screw 25 passes in threaded engagement with a lug 27 secured to the bottom plate 20. A hand wheel 28 is provided so that by rotation of the wheel 28 the plate 20 may be accurately rotated with respect to the plate 17. Since, as will be brought out hereinafter, the die is held by means of chuck jaws secured to the plate 20, it will be clear that actuation of the wheel 28 produces rotational adjustment of the die.

Secured to the underside of the plate 20 are guides 29 for the chuck jaws. There are two pairs of the guides 29 for each pair being axially aligned and the pairs being disposed at right angles to each other. The chuck jaws proper are indicated at 30, and they slide within the guides 29. Their movement is controlled by means of screws 31 provided with knobs 32 and it will be seen that the chuck jaws are provided with the axial groove or slot 33 to accommodate the screws 31 and that a nut having a threaded hole to engage the screw 31, and indicated at 34, is disposed in a transverse slot 35 in the chuck jaw 30. It will be clear from the foregoing that by rotating the wheel 32, the chuck jaw 30 is advanced or retracted.

From the foregoing, it will be understood that by retracting one and advancing the other chuck jaw of a pair, the position of the die along one axis may be adjusted. Similarly, by advancing one and retracting the other of the other pair of chuck jaws, the position of the die may be adjusted along an axis at right angles to the first mentioned axis.

Guides 36 for the stack of labels are provided as is conventional and these guides are adjusted by means of the screws 37 as is well known in the art.

The ram is indicated in FIG. 4 at 38 as being near the top of its stroke and the ram is actuated by a piston 39 operating within a cylinder 40 (FIG. 6).

THE HYDRAULIC CIRCUIT

With reference to FIG. 6, there is shown a fixed volume pump PF driven by an electric motor EM. The pump is supplied through a strainer STR. A maximum pressure relief valve 41 is provided in the pressure line from the pump. Fluid from the pump is fed to the ram circuit through a four-way valve 42 operated by the solenoids 42a and 42b. When the valve 42 moves to the right, fluid from the pump passes through the line 43 and the valve and the line 44 to the top of the cylinder 40 to move the piston 39 down. The return flow passes through the line 45 and the valve 42 into the line 46 and thence through the valve 47 to the sump 48 when the valve 47 is in neutral position. When the valve 42 is moved to the left, fluid from the line 43 crosses over to the line 45 and enters the cylinder below the piston 39 to move the piston up and the return flow passes through the line 44 and crosses over in the valve 42 into the line 46 as before.

The shuttle cylinder is indicated at 49 and the shuttle piston at 50. The movement of the shuttle is controlled by the valve 47 which is operated by the solenoids 47a and 47b. When the valve 47 moves to the right, fluid in the line 46 flows through the line 51 to the left side of the cylinder 40 to move the shuttle in. The return flow passes through the line 52 and the valve 47 to the sump 48 through a filter FLT. When the valve 47 is moved to the left, fluid from the line 46 crosses over into the line 52 and enters the cylinder 49 behind the piston 50 to move the shuttle in. The return flow through the line 51 crosses over in the valve 47 to the line 53 and returns to the sump 48. A pressure relief by-pass valve is indicated at 54 and is set at a relatively low value. Thus, by way of example, the pressure in the ram circuit may be on the order of 1,100 psi and thus the line 46 leading from the valve 42 would carry approximately 1,100 psi. The valve 54 may be set at a figure of, say 65 psi, so that pressure at the valve 47 is thus limited to about 65 psi by virtue of the by-pass to sump through the check valve 54. This provides an inherent safety feature in the apparatus in that with a relatively low pressure on the shuttle piston, an average operator can hold the shuttle against movement without exerting a great deal of strength. Nevertheless, an additional safety feature is provided which will be described in connection with the electrical circuit.

THE ELECTRICAL CIRCUIT

Referring now to FIG. 7, the electrical supply is provided by the leads 55, 56. A main disconnect switch is shown at 57 and the motor which drives the pump is indicated at M. The motor is provided with the usual overload limit switches as well known in the art. A pilot light is indicated at PL. Across the lines 55 and 56 is a circuit including the safety switch LS1, a stop button, a start button provided with a holding circuit and a control relay CR1. When the start button is depressed, a holding circuit is set up as is well known, so that it is not necessary to hold the start button in; and this energizes CR1 which actuates to close the contacts CR1-A and open the contacts CR1-B. The opening of the contact CR1-B cuts out the shuttle and ram jogging circuit and energizes the automatic "in" and "out" and "up" and "down" circuits. The various limit switches in these circuits are designated by the letters LS plus a numeral and it will be seen that certain of them are paired with

one being normally closed and one being normally open. In the case of LS1, it will be seen that this is paired with LS1-A, both of which are normally closed. This is the safety switch. The switches LS4 and LS4-A are paired with one being normally open and the other being normally closed. Similarly, LS5 and LS5-A constitute a pair, one of them being normally closed and the other being normally open, and the same is true of LS6 and LS6-A.

10 In the position of the various switches shown in FIG. 7, when the start switch is pressed and held in by the holding circuit generally indicated at 58, the control relay CR1 operates to close the contact CR1-A, energizing the automatic "in" and "out" and "up" and "down" circuits and opens the contacts CR1-B to the jogging circuits. Current passes through the switches LS4-A and LS6-A to move the valve 42 to the "down" position. When the ram reaches the bottom of the stroke, LS6 is actuated to open the switch LS6-A and close LS6. This shifts the valve 42 to stop "down" movement of the ram and shifts the valve 47 to start "in" movement of the shuttle.

25 At the end of the shuttle "in" stroke, the shuttle operates LS2, closing it to energize the ram "up" circuit through LS1-A. As the ram starts up, it actuates LS4 to maintain the ram "up" circuit and also opens LS4-A in the ram "down" circuit. It will be seen that LS4 takes over from LS2 in holding the "up" circuit closed. Initial movement of the ram also actuates LS5 to open LS5 and close LS5-A to energize the shuttle "out" circuit. LS5 is actuated by a long cam shown in FIG. 4 at 59 which holds the shuttle out until the ram returns to the bottom of its stroke. As the shuttle reaches the end of its "out" movement, it actuates LS3 to open the shuttle "out" circuit and stop the shuttle in its "out" position. As the ram reaches the top of its stroke, LS4 rides off the long cam 60 to open the ram "up" circuit and energizes the ram "down" circuit.

30 40 The safety switch LS1 is mounted in a position to be actuated by the hand or arm of an operator when his hand or arm is still positioning the label stack while the shuttle is moving in. The safety switch is shown in more detail in FIG. 5. It has an actuating button 61 which is held in position to maintain LS1 closed by means of an arm 62 pivoted at 63 and biased in a counterclockwise direction by a hairpin spring 64. An actuator plate 65 is pivoted at 66 and pivotally connected to the arm 62 at 67. As seen in FIG. 5 (or as viewed from the front of the machine), the shuttle would move toward the left and the plate 65 is positioned to be hit by the hand or arm of an operator. When the plate 65 is touched it rocks in a clockwise direction about at pivot 66 and by virtue of the general connection 67 it rocks the arm 62 in a clockwise direction about to pivot 63 against the bias of the spring 64 and thus permits the bottom 61 to move toward the right to open LS1. As clearly seen in the wiring diagram, the opening of LS1 and LS1-A opens the ram "up" circuit and also opens the circuit to CR1 to stop the machine.

45 55 60 The jogging circuit can only be used before the start button is pushed or after LS1 has been actuated or opened. Under those conditions, CR1-A is open to cut out the automatic circuits and CR1-B is closed to energize the jogging circuits. A separate "in" and "out" switch is provided for the shuttle and for the ram and these are useful in setting up an adjustment.

It will be clear that modifications may be made without departing from the spirit of the invention and, therefore, no limitation not expressly set forth in the claims is intended or should be implied.

The embodiments of the invention in which an exclusive property or privilege is claimed are defined as follows:

1. A label die cutting machine comprising a main frame, a vertically disposed ram cylinder mounted in said frame, a piston in said cylinder, a ram connected to said piston, a die holder secured to said frame in a coaxial position above said ram, said ram, when moved upwardly by said piston, being adapted to force a stack of labels positioned on said ram through a die held in said die holder to cut the same, said machine having a slotted table extended laterally, a shuttle cylinder horizontally mounted under said table, a piston in said shuttle cylinder, a shuttle on said table and connected to said shuttle piston through said slot, and adapted, upon energization of the shuttle piston, to push a stack of labels placed on said table into position on said ram, a hydraulic circuit including a pump and solenoid actuated valves for feeding hydraulic fluid to said ram cylinder and said shuttle cylinder, and limit switches in an electric circuit including said solenoids and a motor for driving said pump, said limit switches being actuated by said ram and shuttle respectively to cause the ram and shuttle pistons to operate in timed relation to each other, said die holder comprising a top plate having a circular aperture, a bottom plate having an aperture, said bottom plate having a plurality of vertically disposed rollers engaging the inner periphery of the circular aperture in said top plate, whereby it may be rotationally adjusted with respect to said top plate, a plurality of clamps for clamping said bottom plate to said top plate in a desired position of adjustment, said bottom plate carrying two pairs of adjustable chuck jaws disposed at right angles to each other.

2. A machine according to claim 1, wherein each of said chuck jaws comprises a rectangular block mounted for sliding movement in guides in said bottom plate, said block having an axial groove to accommodate a screw and a transverse slot to accommodate a nut, a nut of a configuration to fit snugly in said transverse slot and having a threaded hole in alignment with said axial groove, and an adjusting screw rotatably se-

cured to said bottom plate in axially fixed position and extending in said axial slot and passing in threaded engagement through said nut.

3. A machine according to claim 1, wherein said pump feeds fluid at relatively high pressure to a circuit including said ram cylinder through a four-way valve, which in one position passes fluid to the bottom of said cylinder to raise the ram, and in another position passes fluid to the top of the cylinder to lower the ram, and 10 also at all times passes fluid to a circuit to the shuttle cylinder; said shuttle cylinder circuit including a pressure relief by-pass valve to limit the fluid pressure in said shuttle cylinder circuit to a relatively low value, said shuttle cylinder circuit including a four-way valve 15 which in one position passes fluid to one end of the shuttle cylinder to move the shuttle in and in another position passes fluid to the other end of the shuttle cylinder to move the shuttle out.

4. A machine according to claim 3, wherein the ram control valve is moved to the "up" position by a solenoid energized by actuation of a limit switch at the end of the "in" stroke of the shuttle, and is moved to a "down" position by actuation of a solenoid energized by a limit switch at the top of the stroke of the ram.

5. A machine according to claim 3, wherein the shuttle control valve is moved to the "in" position by a solenoid energized by actuation of a limit switch at the bottom of a stroke of the ram, and is moved to the "out" position by an actuation of a solenoid energized by a limit switch at the beginning of the "up" stroke of the ram.

6. A machine according to claim 3, wherein a normally closed safety switch is disposed to be opened by the hand or arm of an operator if the operator's hand or arm is still on a stack of labels being pushed by a shuttle into position on the ram, the opening of said safety switch preventing "up" movement of the ram and stopping "in" movement of the shuttle.

7. A machine according to claim 3, wherein jogging circuits are provided for inching the ram "up" or "down" and for inching the shuttle "in" or "out," said jogging circuits being actuatable only when the main "in" and "out" and "up" and "down" circuits are deactivated.
